BAG WITH COLORING CAPSULE

Howard A. Rohdin, Glen Ridge, N. J.

Application August 9, 1949; Serial No. 109,368

1 Claim. (Cl. 206—47)

1

It is an object of this invention to provide an improved bag for oleomargarine in which the mixing of coloring matter with the margarine is facilitated and which will be easy and cheap to manufacture.

It is a further object of this invention to provide a bag as aforesaid which greatly expedites the distribution of the coloring matter throughout the oleomargarine.

It is a further object of this invention to provide a method of using the bag as aforesaid which will greatly shorten the time and reduce the effort incident to mixing coloring with margarine.

The above and other objects will be made clear from the following detailed description taken in connection with the annexed drawings, in which:

Figure 1 is a plan view of one form of the improved bag;

Figure 2 is a plan view of a modification of the form illustrated in Figure 1;

Figure 3 is a plan view of a different application of the invention;

Figure 4 is a modification of the form illustrated in Figure 3;

Figure 5 is a further modification of the form illustrated in Figure 3;

Figure 6 illustrates an essential step in the improved method of using the bag;

Figure 7 is a plan view of a different type of bag; and

Figure 8 is a section on the line 8—8 of Figure 7.

In my Patent No. 2,469,521 I showed a package in which a capsule of coloring matter is secured in a triangular ear which is formed incident to closing the package. The package disclosed in that patent is excellent where the package is formed on machines of the general type illustrated in Patent No. 2,469,521 and where in general the oleomargarine packer is willing to broaden his packaging steps. The present invention is directed toward making it possible to assemble and secure a capsule of coloring matter in a bag without the necessity of resorting to redesign of the filling machinery.

Figure 1 shows a bag 10 having an open mouth 12. For the sake of simplicity of illustration this is shown as a seamless tube but obviously any of the conventional single or double seam tubes could be used. A heat seal seam 14 is formed across one end of the bag. A capsule of coloring matter 16 is dropped into one corner of the bag and a diagonal seam 18 is formed which at one end merges with the transverse seam 14 and at

2

the other end closely approaches one edge 20 of the bag 10 thus defining a narrow channel 22 through which the coloring matter may pass on rupturing of the capsule 16 but which is too narrow to permit passage of the capsule itself. When the bag is filled and brought to rectangular position the triangular portion 24 defined by transverse seam 14, the seam 18 and the edge 20 remains as a flat protruding ear. Upon rupture 10 of the capsule the coloring matter tends to move longitudinally down the length of the bag which facilitates quick and even distribution of the color throughout the margarine.

In Figure 2 there is shown a bag 30 having an open mouth 32. It is closed at the other end by a transverse seam 34. A capsule of coloring matter 36 is placed in one corner of the bag and is locked away by an inlying seal 38 which with the edge 40 of the bag defines a passageway 42. 15 A series of seals 44 are provided closely adjacent the edge 40 and spaced apart to define openings 46 along that edge. This positively guides the coloring matter passing through the channel 42 down the length of the bag.

25 In Figure 3 I show a bag 50 having an open mouth 52 and having at the opposite end a transverse heat seal seam 54. A capsule of coloring matter 56 is placed in one corner of the bag and an arcuate heat seal 58 is provided which at one end merges with the transverse seam 54 and at the other end defines with the edge 60 of the bag a channel 62. This construction reduces the volume of the sealed-off corner and assures minimum waste of coloring matter in the corner.

In Figure 4 I show a bag 70 having an open mouth 72 and being closed at its opposite end by a heat seal seam 74. A capsule of coloring matter 76 is placed in the corner and secured there by an arcuate seam 78 similar to the arcuate seam 58 in Figure 3. A series of heat seals 80 are formed adjacent the edge 82 of the bag 70 and are spaced apart to provide passageways 84. This construction as described with reference to Figure 2 facilitates distribution of the coloring matter down the length of the bag.

35 In Figure 5 I show a bag 90 having an open mouth 92 and being closed at its opposite end by a transverse heat seal seam 94. A capsule of coloring matter 96 is placed in the corner of the bag and secured there by an arcuate heat seal comprising a series of relatively short seals 98 which are spaced to provide a plurality of channels 100. These facilitate distribution of the margarine not only toward the edge 102 of the bag but into its upper surface.

A further useful modification is shown in Figures 7 and 8. Here the coloring matter 200 is inserted in either liquid or paste form into one corner 202 of a bag 204, the end of which adjacent said corner has been closed by a heat seal seam 206. A further seam 208 runs across the corner and completely blocks the corner from the body of the bag. The seal is applied, however, under a lighter degree of heat and pressure than is used for either the top or bottom closure and will part when the corner is manipulated manually. This arrangement has several important advantages. In the first place there is no problem of disposal of the capsule. In the second place the entire volume of the bag is made available for manipulating the margarine and, in the third place, due to the lack of capsule the coloring matter can be kept quite flat and the space occupied by the corner, therefore, is greatly diminished.

While with any of the constructions above described there will be at the end containing the capsule a protuberant ear, the opposite end of the package will be closed so that the closure is rectangular and lies in a plane at right angles to the length of the package. In use the package is removed from the refrigerator and permitted to warm up until it is soft enough to be easily workable. In ordinary practice it is merely necessary to rupture the capsule and then to manipulate the package until the coloring matter is thoroughly and evenly mixed with the margarine. I have found that if, when the package is removed from the refrigerator, it is placed upright with the protuberant ear at the top and the capsule is then ruptured before softening occurs the coloring matter naturally will channel down the side of the package and by the time the package is soft enough to manipulate the coloring will be so far distributed that complete mixing will take place in one-third to one-fourth the time ordinarily required.

The action above discussed is illustrated in Figure 6 wherein the bag 10 of Figure 1 has been

filled and up-ended to bring the ear 24 and the capsule 16 into the upper left corner. With the oleomargarine in a hard, solid condition the capsule 16 is ruptured and the bag replaced in its original carton which permits the capillary action between the wall of the bag and the oleomargarine to draw the coloring matter down the full length of the bag while the margarine softens to a point suitable for manipulation. In case the form of Figures 7 and 8 is used the corners would be manipulated to open the frangible seal 208 and permit the coloring matter 200 similarly to traverse the bag.

I claim:

15. A bag comprising a flattened tube formed of flexible material and having one end closed by a transverse heat seal seam, a capsule of coloring matter in one corner of the bag adjacent said transverse seam, said capsule being secured in said corner by a supplementary heat seal seam which terminates just short of the edge of said flattened tube to define a channel for the passage of coloring matter, which channel is sufficiently small not to pass the capsule itself, there being a plurality of spaced heat seals formed parallel to the bag edge and in alignment with the free end of said supplementary seal to provide a channel extending the length of the bag and a series of passageways from said channel to the interior of the bag.
